WHEEL TOY

Max R. Ahlstrom, Orange City, Iowa

Application May 1, 1956, Serial No. 41,285

Term of patent 14 years

(Cl. D34—15)

Figure 1 is a side view of a wheel toy showing my new design.

Figure 2 is an edge view looking toward the front of the toy.

Figure 3 is an end view of the said wheel toy.

Figure 4 is an edge view looking toward the rear of the toy.

I claim:

The ornamental design for a wheel toy, as shown.
